UNITED STATES PATENT OFFICE.

LAWRENCE W. SCUDDER, OF CHICAGO, ILLINOIS.

HEATING METHOD AND DEVICE.

Application filed November 16, 1925. Serial No. 69,327.

To all whom it may concern:

Be it known that I, LAWRENCE W. SCUDDER, a citizen of the United States, residing at Chicago, in the county of Cook and State of Illinois, have invented a certain new and useful Improvement in Heating Methods and Devices, of which the following is a specification.

My invention relates generally to a hot air heating installation and to a method of heating. I illustrate it as applied to an oil burning installation including a furnace and an oil burner, but it may be used equally advantageously with other fuels. One object of my invention is the provision of such a hot air heating method and plant which is particularly adaptable for domestic dwelling house use. Another object is the provision of such a plant in which the flow of air through the air heating jacket or chamber about the furnace is positively and thermostatically controlled. Another object is the provision of means for simultaneously controlling the flow of air through the air jacket and about the furnace, the flow of air to the burner itself and the flow of fluid fuel to a burner. Other objects will appear from time to time in the course of the specification and claims.

I illustrate my invention more or less diagrammatically in the accompanying drawings wherein—

Figure 1 illustrates a vertical section through my installation shown as used with an oil burner; and

Figure 2 is a similar section through an installation in which coal is burned.

Like parts are indicated by like symbols throughout the specification and drawings.

A generally indicates any suitable furnace consisting of three separate sections A¹ A² A³ although any suitable structure might be employed. Said sections are mounted upon a lower section A⁴ within which is enclosed the oil burner later to be described. A⁵ is a door giving access to the furnace proper.

B is an air jacket surrounding and enclosing the furnace and forming about it the air chamber B¹. Through it penetrates the flue passage A¹⁰ which extends from the upper furnace section A³. B² B³ B⁴ are any suitable air ducts or passages leading to the rooms to be heated and B⁵ is a returning air

duct or passage adapted to deliver to the air 55 chamber B¹ the cool air returned from the room or rooms.

Positioned within the passage B⁵ is any suitable air impelling means herein diagrammatically illustrated as a fan C adapted to 60 be actuated by an electric motor C¹, driven from any suitable electric power source not herein shown.

Referring to Figure 1, K K¹ are electric conductors in circuit with the motor C¹ and 65 extending to any suitable electric power source. K² is any suitable switch lever pivot as at K³ and adapted to be thermostatically controlled for example by means of the stem K⁴ actuated by the thermostatically responsive element K⁵. K⁶ are a plurality of abutments or contacts adapted to be engaged by the outer end of the switch K². Referring to Figure 2, I have illustrated a hand control switch K¹⁰. 75

In the form herein shown I position the fan C well within the termination of the passage B¹ thus forming a relatively restricted air or compression chamber C³. One portion of the chamber is more or less segregated by the downwardly and inwardly projecting flange C⁴, the bulk of the air to pass however through the opening C⁵. 80

D generally indicates a firepot or burner structure including a central combustion 85 chamber D¹ surrounded by a circumferential wall D² penetrated by a plurality of relatively small apertures D³ which communicate with the outer circumferential air chamber D⁴ which is closed by the circumferential wall D⁵. Communicating with the air chamber D⁴ is a pipe D⁶ having the control valve D⁷, extending to the air chamber C³ within the flange C⁴. The bottom of the combustion chamber is arcuately formed as at D⁸ and 90 is preferably filled with a bed of sand or similar finely divided material D⁹.

E is a fuel supply line from any suitable fuel storage supply source which communicates with the carburetor casing generally 100 indicated as E¹ and has the control valve E². The casing is provided with a flat chamber E³ and the float E⁴, the float controlling the lever E⁵ pivoted as at E⁶ and provided with the valve member E⁷ which seats as at 105 E⁸ at the inlet of the fuel passage E. E⁹ is a fuel line from the float chamber to the bottom of the combustion chamber where it

2
discharges as at E¹⁰ to the sand bed. E¹¹ is an air line extending from the pressure chamber C³ and the flange C⁴ to the carburetor casing, discharging downwardly as 5 at E¹² in line with the float. The air line E¹¹ has the control valve E¹³.

Referring to Figure 2 the air delivered by the fan C circulates through the air chamber B¹ past the walls of the fire box or furnace A². However in place of the oil burner illustrated in Figure 1 I employ any suitable grate arrangement G adapted to support a bed of coal or other suitable solid fuel. The wall of the lower section A⁴ is penetrated by 15 a plurality of apertures G¹ whereby air from the air chamber B¹ is permitted to circulate upwardly through the grate bars G and outwardly through the flue A¹⁰.

It will be realized that whereas I have 20 illustrated a practical and operative device that nevertheless many changes might be made in the size, shape, number and disposition of parts and that I wish my description and drawings to be taken as in a 25 broad sense diagrammatic or illustrative rather than as limiting me to my specific showing.

The use and operation of my invention are as follows:

30 I employ any suitable type of furnace adaptable for use with a hot air heating system. I surround the furnace with a hot air jacket or housing B adapted to permit or cause the heating by the furnace of the 35 air passing therethrough. The air is drawn off by the usual vents or ducts B² B³ and B⁴ for heating use. I provide a main return duct or return flow B⁵ which receives the cool air from the house. Obviously I might 40 use more than one of such ducts but I find one sufficient and preferable. In such duct I position any suitable means, for example, the fan C, for drawing or forcing a flow of air therethrough.

45 It is preferably made thermostatically responsive to the house temperature, the particular thermostat and electrical connection therefor forming no part of the present invention. Any means suffices whereby the 50 fan will be actuated when the house temperature at a given point or points falls to or below a predetermined norm or sub-norm.

However I have diagrammatically illustrated, in Figure 1, a thermostatic arrangement whereby the switch K² in the circuit K K¹ is actuated by the thermostatically responsive element K⁵. It may be either moved into inoperative position, as shown in the drawing, or may be positioned upon one 60 of the contacts K⁶, a plurality of contacts being provided to permit of the actuation of the fan C¹ at varying speeds. In Figure 2 I illustrate a manually operated switch member K¹⁰.

65 My invention may be most broadly stated

as a method of heating wherein the air circulation about the combustion chamber or heating unit is increased in unison with and in proportion to an increase in the supply of air for combustion to the combustion chamber. My invention is not limited to the employment of any particular fuel and is herein shown as employed with an oil burner and with a coal burner. Obviously any other fuel may be employed, in which it is necessary, for combustion, to supply air to the zone of combustion, or in which combustion can be controlled by varying the supply of air.

A particularly happy use of my invention 80 is its application to the utilization of a fluid fuel, for example oil or gas. In such case I may control in proportion not merely the circulation of the air to be heated and the flow of the air for combustion, but also 85 the flow of the fuel itself.

Referring to Figure 1, by providing the separate air connection between such blower and the air chamber D⁴ surrounding the oil burner combustion chamber I insure an increase in the supply of air to said combustion chamber in response to the thermostatic actuation of the blower. At the same time, the blower, through the air line E¹⁰, directs 90 a pressure upon the float of the carburetor and thus it causes or permits an increased flow of fuel to the oil combustion chamber through the lifting of the carburetor valve. The result of the simultaneous increase of 95 the fuel and oil supply is a much increased 100 flame and a greater heating of the furnace wall. Since this heating is accompanied by an increased flow of cold air about the furnace and across the wall, the increased heat is absorbed by the air. By properly proportioning furnace and combustion chamber and by proper adjustment of the air and oil passages, I am able to increase the flame and to increase the temperature of the outer 105 wall of the furnace and thus to increase the 110 temperature of the flowing air and of the house without substantially increasing the temperature of the exhaust gases passing upwardly through the flue.

Referring to Figure 2 I illustrate a 115 variant form of my device in which there is a normal flow of air from the air jacket to the zone beneath the bed of coal in the combustion chamber. This flow is through apertures in the air jacket at a level lower than 120 the grate bars. When the air circulation about the combustion chamber is increased, as by the employment of a fan or blowers, the flow of air into the combustion zone itself 125 is increased and an increased air pressure is caused beneath the bed of coals, or beneath the level of combustion of the substance being burned. The result is an upward draft and a consequent increase in the activity of 130 combustion.

I claim:—

1. The method of hot air heating which includes the provision of a circulation of air to and past a zone of combustion, and the provision of an air supply to the zone of combustion and the unitary variation and control of such air circulation and air supply. 70
2. The method of hot air heating which includes the provision of a circulation of air to and past a zone of combustion, and the provision of an air supply to the zone of combustion and the provision of unitary means for simultaneously increasing or diminishing such air circulation and air supply. 75
3. The method of hot air heating which includes the provision of a circulation of air to and past a zone of combustion, and the provision of an air supply to the zone of combustion and the provision of unitary means for simultaneously increasing or diminishing such air circulation and air supply, in response to variations in the temperature of the area to be heated. 80
4. The method of hot air heating which includes the provision of a circulation of air to and past a zone of combustion, the provision of a supply of fluid fuel to such zone of combustion, the provision of an air supply to the zone of combustion, and the provision of unitary means for simultaneously increasing or diminishing the air circulation, the fuel supply and the air supply. 85
5. The method of hot air heating which includes the provision of a circulation of air to and past a zone of combustion, the provision of a supply of fluid fuel to such zone of combustion, the provision of an air supply to the zone of combustion, and the provision of unitary means for simultaneously increasing or diminishing the air circulation, the fuel supply and the air supply, in response to variations in the temperature of the area to be heated. 90
6. The method of hot air heating which includes the provision of a circulation of air to and past a zone of combustion, and the provision of an air supply to the zone of combustion and the provision of unitary means for simultaneously and proportionately varying such air circulation and air supply. 105
7. The method of hot air heating which includes the provision of a circulation of air to and past a zone of combustion, the provision of a supply of fluid fuel to such zone of combustion, the provision of an air supply to the zone of combustion, and the provision of unitary means for simultaneously and proportionately varying the air circulation, the fuel supply and the air supply. 110
8. In an oil burning installation, a furnace, a burner associated with said furnace, means for supplying air thereto, an air jacket about said furnace, air discharge means leading thence and air return means extending thereto, means for simultaneously increasing the flow of air to said burner and for proportionately increasing the flow of air through said air jacket and about said furnace. 120
9. In an oil burning installation, a furnace, a burner associated with said furnace, means for supplying air thereto, an air jacket about said furnace, a plurality of air ducts leading thence and a return air duct thereto, and means for simultaneously and proportionately increasing the flow of fluid fuel to the burner, the flow of air to the burner, and the circulation of air through the air jacket and about the furnace. 125
10. In an oil burning installation, a furnace, a burner associated with said furnace, means for supplying air thereto, an air jacket about said furnace, a plurality of air ducts leading thence and a return air duct thereto, means for simultaneously increasing the flow of air to said burner and for proportionately increasing the flow of air through said air jacket and about said furnace, including a fan associated with the return air duct. 130
11. In an oil burning installation, a furnace, a burner associated with said furnace, means for supplying air thereto, means for supplying a fluid fuel thereto, an air jacket about said furnace, a plurality of air ducts leading thence and a return air duct thereto, and means for simultaneously and proportionately increasing the flow of fluid fuel to the burner, the flow of air to the burner, and the circulation of air through the air jacket and about the furnace, including a fan associated with the return air duct. 135
12. In a heating installation, a furnace, an air jacket surrounding it, a plurality of air ducts leading thence, a return air duct thereto, a fan in the line of said return duct and a thermostatic connection therefor, an oil burner in said furnace comprising a combustion chamber and air chamber surrounding said combustion chamber, the circumferential wall of the combustion chamber being penetrated by a plurality of apertures, communicating with said air chamber, an oil line extending to said combustion chamber, a carbureter in said oil line and an air connection between said fan and said circumferential air chamber and said fan and said carbureter. 140
13. In a heating installation, a furnace, an air jacket surrounding it, a plurality of air ducts leading thence, a return air duct thereto, a fan in the line of said return duct, a burner in said furnace, a fuel line extending to said combustion chamber, a control valve in said oil line, and an air connection be- 145

tween said fan and said burner, and between
said fan and said control valve.

14. In a heating installation, a furnace, a
burner, associated with said furnace, includ-
ing a combustion chamber, an oil line to said
oil burner and flow controlling means there-
in, an air jacket about said furnace, air dis-
charge means leading thence, air return
means adapted to return cold air to said air
jacket, means for simultaneously increasing
the flow of air within said air jacket about
said furnace, increasing the flow of air from
said air chamber to said combustion cham-
ber and for increasing the flow of oil along
said oil line.

15. In a heating installation, a furnace, a
burner, associated with said furnace, includ-
ing a combustion chamber, an oil line to said
oil burner and flow controlling means there-
in, an air jacket about said furnace and a
plurality of air ducts leading thence, a re-
turn duct to said air jacket, means for si-
multaneously increasing the flow of air with-
in said air jacket about said furnace, increas-
ing the flow of air from said air chamber to
said combustion chamber and for increasing
the flow of oil along said oil line, compris-

ing air impelling means associated with the
air inlet duct.

16. In a heating installation, a furnace, an
oil burner associated with said furnace,
means for supplying air thereto, an air jacket
about said furnace, a plurality of air ducts
leading thence and a return air duct there-
to, and means for simultaneously increasing
the flow of oil to said oil burner increasing
the flow of air to said oil burner and in-
creasing the flow of air through said air
jacket and about said furnace.

17. In a heating installation, a furnace, an
oil burner associated with said furnace,
means for supplying air thereto, an air
jacket about said furnace, a plurality of air
ducts leading thence and a return air duct
thereto, and means for simultaneously in-
creasing the flow of oil to said oil burner in-
creasing the flow of air to said oil burner
and increasing the flow of air through said
air jacket and about said furnace, compris-
ing a fan in the line of said return air duct.

Signed at Chicago, county of Cook and
State of Illinois, this 11th day of November
1925.

LAWRENCE W. SCUDDER.
